CLAIM

The ornamental design for a shoe midsole, as shown and described.

DESCRIPTION

FIG. 1 is a left side view of a shoe midsole showing our new design;

FIG. 2 is a right side view thereof;

FIG. 3 is a front quarter view thereof;

FIG. 4 is a front perspective view thereof; and,

FIG. 5 is a rear view thereof.

The broken lines are for environmental purposes only and form no part of the claimed design.

1 Claim, 4 Drawing Sheets
